M. J. Trainor

WITNESS:

UNITED STATES PATENT OFFICE.

THOMAS CONDELL, OF VANCOUVER, BRITISH COLUMBIA, CANADA.

TOY.

Application filed December 27, 1924. Serial No. 758,437.

To all whom it may concern:

Be it known that I, THOMAS CONDELL, a subject of the King of Great Britain, residing at Vancouver, Province of British Columbia, and Dominion of Canada, have invented new and useful Improvements in Toys, of which the following is a specification.

This invention relates to toys, and more particularly to a toy gun designed to discharge a fire cracker after igniting the fuse thereof.

One object is to provide a gun or pistol which may be made at very low cost, and which shall be capable of use for discharging various kinds of articles, as missiles, including fire crackers.

A further object is to provide propelling means of resilient form adapted to impart a blow which will fire a percussion element or which will propel a small object such as a solid missile.

A still further object is to employ a missile comprising the well known type of fire cracker having connected therewith a percussion element.

With the foregoing and other objects in view, the invention consists in the novel construction and arrangement of elements described and claimed, it being understood that modifications may be made within the scope of the claim without departing from the spirit of the invention.

In the drawings, Figure 1 shows the device chiefly in vertical section; Figure 2 is a view in side elevation; Figure 3 is in horizontal section and top plan, the section being on line 3—3 of Figure 1; Figure 4 is a detail view of the missile; Figure 5 shows a slight modification in which the fuse of the missile has a percussion member formed directly thereon.

The barrel of the gun or pistol is designated 10 and is provided with a longitudinal slot 11 extending toward the breech.

The handle 12 may be formed of tubular material and includes a downwardly extending portion 13, a loop 14, and an upward extension 15 having an upper open end.

The portion 13 of the handle is connected rigidly with a slotted sleeve 16, the slot being in alignment with the slot of the barrel. The sleeve 16 has less diameter than the barrel and extends into the breech portion thereof,

and the bore of the sleeve is tapered, permitting a fire-cracker or other missile to be wedged therein sufficiently tight to prevent accidental displacement.

As shown in Figure 1, the barrel may be made in one piece with the tubular handle portion.

A trigger 18 is pivoted at 19, and a U-shaped or arch shaped spring 20 has one end extending into the open end of the trigger element comprising the handle, the other end of the spring projecting into the slot of the barrel for imparting a blow to the object to be discharged.

When the spring 21 is placed under compression, it will engage the trigger, the release of the trigger allowing the spring to suddenly expand and impart a blow to the missile previously placed in the tapered bore.

Shot of suitable size may be employed, or even wooden missiles. A special feature is the provision of a fire-cracker 24 adapted to be ignited and discharged upon the release of the trigger. The head 25 of a match may be inserted into the body of the cracker adjacent to the fuse and allowed to project slightly from the end, the fuse being shortened if desired. This match head or other similar element will be ignited upon the impact of the spring, and the cracker discharged and ejected from the gun. However, the fuse may have a percussion element formed directly thereon, as shown in Figure 5.

A spring of greater or less strength may be employed, a weak spring being preferable if the gun is to be used by small children. The element 27, connected with the handle by a clip 28 projects under the trigger, as shown.

What is claimed is:—

In a toy gun, a barrel slotted longitudinally, a sleeve slotted longitudinally and connected with the barrel, the slotted portions of the barrel and sleeve being in alignment, said sleeve having a tapered bore of less diameter at one end than the bore of the barrel, a handle connected with the sleeve, a spring projecting into and operable in the slotted portions of the sleeve and barrel, for imparting a blow to a missile, and means for retaining the spring under compression.

In testimony whereof I affix my signature.

THOMAS CONDELL.
